UNITED STATES PATENT OFFICE.

EDWARD T. HURLEY, OF CINCINNATI, OHIO.

DESIGN FOR AN ARTISTIC BRONZE CANDLESTICK OR SIMILAR ARTICLE.

Application filed March 12, 1928. Serial No. 25,801. Term of patent 7 years

To all whom it may concern:

Be it known that I, EDWARD T. HURLEY, a citizen of the United States of America, and a resident of Cincinnati, in the county of Hamilton and State of Ohio, have invented a new, original, and ornamental Design for an Artistic Bronze Candlestick or Similar Article, of which the following is a specification, reference being made to the accompanying drawing, forming a part thereof.

Fig. 1 is a side elevational view of a bronze candlestick showing the design.

Fig. 2 is a fragmental front elevational view of the design shown in Fig. 1.

I claim:

The ornamental design for an artistic bronze candlestick or similar article as shown.

EDWARD T. HURLEY.
